UNITED STATES PATENT OFFICE.

ARTHUR J. ADAMS, OF CHICAGO, ILLINOIS, ASSIGNOR, BY MESNE ASSIGNMENTS, TO
WILLIAM S. FERRIS, OF ELKHART, INDIANA, AND ALEXANDER B. LEITH, OF
CHICAGO, ILLINOIS, TRUSTEES.

BABY-CARRIAGE.

1,090,511.

Specification of Letters Patent. Patented Mar. 17, 1914.

Application filed November 19, 1904. Serial No. 233,489.

To all whom it may concern:

Be it known that I, ARTHUR J. ADAMS, a citizen of the United States, residing at Chicago, in the county of Cook and State 5 of Illinois, have invented a new and useful Improvement in Baby-Carriages, of which the following is a specification.

My invention relates particularly to go carts, or folding baby-carriages, peculiarly 10 adapted for use in traveling.

My primary object is to provide a thoroughly practicable and durable carriage of the character indicated, provision being made for automatic folding and unfolding 15 so far as consistent with thoroughly commercial practicability.

The present invention constitutes an improvement on the invention set forth and generally claimed in my application No. 20 196,766, filed March 5, 1904.

The invention is illustrated in the accompanying drawings, in which—

Figure 1 represents a side elevational view of my improved folding carriage in its preferred form the handle being broken; Fig. 2, a plan view of the same; Fig. 3, a transverse section taken as indicated at line 3 of Fig. 1; Fig. 4, a broken side elevational view showing the position of certain parts preparatory to locking the brace links serving 30 to support the seat-support; Fig. 5, a side view of the carriage in a folded condition; and Fig. 6, a plan view of the carriage in the folded condition, with the seat and other 35 leather parts removed.

In the preferred construction, A represents a substantially horizontal running-gear frame; B, sleeves pivoted on the side members thereof and equipped with wheel 40 supports, or forks, B¹, in which the wheels are journaled; C, an inclined seat support having its front end connected by a pivot c with the front portion of the running-gear frame; D, a handle having its lower end connected by hinges d with the rear end of the 45 running-gear frame; and E, mechanism connected with the seat support and handle and serving, in the operations of folding and unfolding the handle with relation to the running-gear frame, to lower and raise the seat-support, said mechanism being equipped 50 with means for locking the seat support and

the wheel-supports in the extended positions.

The frame A may comprise U-shaped 55 tubing constituting the front and side members of the frame; the seat support may comprise U-shaped tubing constituting side members and a back member; and the handle may comprise U-shaped tubing with the free 60 lower extremities joined to the free rear extremities of the side members of the running-gear frame. The side members of the running-gear frame are equipped with collars a having shoulders a¹ serving to engage 65 corresponding shoulders with which the sleeves B are provided at their front ends, whereby the forks B¹ are limited in their outward swing when the vertical position is reached. As will be understood, the 70 front and rear forks at either side of the vehicle are connected to be swung to the folded or extended position together. The member C has the seat c¹ connected therewith in any suitable manner. As shown, the 75 seat is supported by leather side pieces c² and a leather back c³; and there is connected with the front edge of the seat and with the front portion of the running-gear frame a foot support c⁴, which preferably is composed principally of leather bearing an inserted foot-board c⁵.

The mechanism E comprises, in the preferred construction, a pair of substantially vertical brace-links e having their upper ends pivotally connected with the rear portions of the side members of the seat support C and their lower ends equipped with locking members e¹; and a pair of two-part flexible links e² having pivotal connection at 80 the rear ends of their rear members with the lower portions of the side members of the U-shaped handle and having pivotal connection at the front ends of their front members with the lower ends of the brace-links e. Each flexible link e² comprise a rear member e³ and a front member e⁴ (Fig. 4), said members being joined by a pivot e⁵. The front end of each member e³ bears a 85 forwardly extending projection e⁶, which constitutes at once a thumb-piece serving in the operation of extending the flexible link, a guard preventing the thumb from being pinched when the joint is straightened, and 90 95 100

a stop limiting the downward movement of the joint, thereby constituting a lock for the joint when the pivot e^5 drops slightly below the line of the members e^3 , e^4 . As will be best understood from Figs. 2 and 4 the rear forks B^1 are equipped at their points of junction with the sleeves B with lugs b having rear vertical surfaces b^1 constituting locking shoulders; and in the rear of these locking shoulders the rear forks B^1 are equipped with horizontal locking shoulders b^2 . The locking members e^1 have vertical and horizontal locking shoulders corresponding with the shoulders just described. It will now be understood that when downward pressure is exerted upon the thumb pieces e^6 of the flexible links e^2 , a downward thrust upon the shoulders b^2 and a forward thrust upon the shoulders b^1 will result, the effect being to lock both the brace-links e and the wheel-supports, when the flexible links are fully extended, as shown in Fig. 1. The locking-members e^1 , and through them the links, or braces, e , are preferably joined by a cross-rod e^7 , as shown in Fig. 3.

The manner in which the carriage is folded and unfolded will be understood without further detailed description. The flexible links e^2 may be struck upwardly at the joints where the pivots e^5 are located, after which the rear end of the seat support may be lifted slightly to permit the locking members e^1 to pass the members b , after which the handle may be folded forwardly upon the running-gear frame to bring it into approximately the plane of the running-gear frame, as shown in Fig. 6. Either before or after the handle is folded, the wheel supports may be swung inwardly to bring the wheels up beneath the running-gear frame and close to the plane of the latter. When it is desired to unfold the carriage, the wheel-supports may be swung downwardly and outwardly till the shoulders a^1 limit further outward movement, the handle may then be swung rearwardly to the position which it occupies in use, and the flexible links e^2 may then be flexed to allow the locking members e^1 to enter their seats, after which the flexible links may be straightened to lock the brace-links e and the wheel-supports. It will be understood, of course, that while the handle is being swung forwardly or rearwardly, the members e^1 ride upon the side members of the running-gear frame, thus swinging the lower ends of the brace-links forwardly or rearwardly, as the case may be, to lower or raise the seat-support. Thus it appears that the raising and lowering of the seat support is effected automatically by the operations of extending and folding the handle with relation to the running-gear frame. Moreover, it appears that in the operation of straightening the flexible

links e^2 the brace-links and the wheel-supports are simultaneously locked; and vice versa, the brace-links and the wheel supports are simultaneously unlocked in the operation of flexing the two-part links e^2 . 70

It will be readily understood that many changes in details of construction within the spirit of my invention are feasible, hence no undue limitation should be understood by the foregoing detailed description, the 75 same having been given for clearance of understanding only.

What I regard as new, and desire to secure by Letters Patent, is—

1. The combination of a running-gear 80 frame, an inclined seat-support having pivotal connection at its front end with the front portion of said frame, a forwardly swinging handle having its lower end pivoted to the rear portion of said frame, a forwardly swinging brace-link pivoted at its upper end to the rear portion of said seat-support, the lower portion of said brace-link finding a support on said frame during the swinging movement, and a flexible two-part link having pivotal connection at its rear end with said handle and pivotal connection at its front end with said brace-link, for the purpose set forth. 90

2. The combination of a running-gear 95 frame, a pivoted seat-support, a pivoted handle, pivoted wheel-supports, a pair of brace-links pivoted at their upper ends to said seat-support and provided at their lower ends with wheel-support locks, and a pair 10 of two-part links having pivotal connections with said handle and the lower ends of said brace-links, each two-part link having a stop for preventing downward flexing, substantially as and for the purpose set forth. 10

3. The combination of a running-gear frame, a pivoted seat-support, a pivoted handle, pivoted wheel-supports, a pair of brace-links pivoted at their upper ends to said seat-support and provided at their 11 lower ends with wheel-support locks, and a pair of two-part links having pivot connections with said handle and the lower ends of said brace-links, one member of each two-part link having a projection adjacent to 11 the connection between the members serving as a thumb-piece, guard and stop, substantially as and for the purpose set forth. 11

4. The combination of a substantially horizontal running-gear frame, an inclined 120 seat-support having its front end pivoted on the front portion of said frame, wheel-supports equipped with two pairs of locking-shoulders, a pair of upright brace-links having their upper ends pivoted to the rear 125 portion of said seat-support and equipped at their lower ends with locking shoulders engaging said mentioned locking shoulders, a handle having its lower end pivoted on the rear portion of said frame, and a pair of 130

flexible two-part links having their rear ends pivoted to the lower portion of said handle and their front ends pivoted to the lower ends of said brace-links, substantially as and for the purpose set forth.

5. The combination of a substantially horizontal running-gear frame, an inclined seat-support having its front end pivoted on the front portion of said frame, a handle 10 having its lower end pivoted on the rear portion of said frame, wheel-supports pivoted on said frame and equipped with lugs having vertical shoulders, a pair of brace-links having their upper ends pivoted on the rear portion of said seat-support and their lower ends equipped with shoulders engaging said first-named shoulders, and a pair of flexible links connecting the handle with the lower ends of said brace-links,

whereby actuation of the brace-links and locking of the brace-links and wheel-supports may be effected, substantially as and for the purpose set forth.

6. In a perambulator the combination of a running gear frame, a seat frame hinged thereon, a handle hinged to said running gear frame, braces for supporting the seat frame pivoted thereto, wheel supports rotatably mounted on the running gear frame, means carried by the said braces for locking the wheel supports, a cross bar connecting said braces together, and a toggle connecting said cross bar with said handle.

ARTHUR J. ADAMS.
